UNITED STATES PATENT OFFICE.

HENRY E. WAITE, OF NEW YORK, N. Y., ASSIGNOR TO THE MOLECULAR TELEPHONE COMPANY, OF SAME PLACE.

TELEPHONE-RECEIVER.

SPECIFICATION forming part of Letters Patent No. 287,742, dated October 30, 1883.

Application filed August 3, 1883. (No model.)

To all whom it may concern:

Be it known that I, HENRY E. WAITE, of the city, county, and State of New York, have invented a new and useful Improvement in 5 Telephone-receivers, of which the following is a full, clear, and exact description, reference being had to the accompanying drawing, making part of this specification.

This invention relates to the reproduction 10 of sounds or combinations of sounds through the agency of undulatory currents of electricity, whereby articulate speech can be transmitted over a telegraph-line.

One form of my instrument is made in the 15 following manner: On one end of a straight-bar permanent magnet is placed a helix, the covered wire wound thereon being in the main-line current. This magnet is secured in a tube of wood, ebonite, or other non-conducting material, this tube being at one end enlarged into a cup inclosing the helix. Upon the rim of this cup is secured, by means of the usual ear-piece, a tympan of wood, ebonite, card-board, glass, brass, cork, or of any equivalent material not subject to the action of magnetism. A thin or thick bar of steel or iron, 20 or of other material capable of being acted on by magnetism, is secured at one end to the inside of the cup, forming an arch over the core 25 of the helix, close to the end of the magnet, within the magnetic field; or it may be held loosely by means of a screw through a slot in each end of the bar, so that the bar, when attracted by the magnet, may glide easily. A 30 short spur projects from the strip of iron directly over the center of the core of the helix, against which spur the tympan is held by the ear-piece.

In the accompanying drawing, which represents the preferred form or construction, A 35 represents the inclosing tube or handle; A', the enlarged chambered end or cap inclosing the coil, and to which the tympan and ear-piece are secured in any usual or preferred manner; b, the bar-magnet; c, the coil placed 40 on the end of the magnet, within the cham-

bered end; d, the tympan, and e the arching bar, of steel or its equivalent magnetic material, referred to, provided with the spur e', resting in contact with the tympan d, as explained. This bar is shown secured at one 50 end to a ledge or annular flange, a, on the inner wall of the chambered head or cup, and has its other end supported upon the ledge on the opposite side, but not fastened thereto, thus leaving it free to slide on the ledge, to accommodate any vibration in the bar e, due to disturbances in degree of polarity in the magnet, said bar being arranged in inductive proximity to said magnet, and in the form of a spring 55 arching over its end, as shown.

I do not confine myself to the use of permanent magnets. Electro-magnets may also be used.

By this construction of an instrument for reproducing articulate speech, the disagreeable metallic nasal sound always resulting from the use of a disk of iron in a telephone, as also the frequent buzzing, are avoided, the articulation is more clear, and the instrument, once 65 adjusted, will remain so.

Having thus described my invention, I claim as new—

The combination, with a magnet, of a bar 75 of iron or steel, or any material capable of inductive action, one end of said bar being attached to a fixed support, the said bar extending over the end of the magnet, but not touching it, and the other end lying on a fixed support, and a plate of any resilient material—such as wood, ebonite, or mica—held down in any convenient manner upon a short spur placed on the middle of the iron bar, immediately over the center of the magnet, substantially as described.

In testimony whereof I have hereunto set my hand this 2d day of August, A. D. 1883.

HENRY E. WAITE.
